UNITED STATES PATENT OFFICE.

JAMES MARSDEN, OF WIGAN, ENGLAND.

DESIGN FOR A PATTERN-CHART.

SPECIFICATION forming part of Design No. 29,602, dated November 1, 1898.

Application filed September 21, 1898. Serial No. 691,567. Term of patent 14 years.

To all whom it may concern:

Be it known that I, JAMES MARSDEN, a subject of the Queen of Great Britain, residing in Wigan, in the county of Lancaster, England,

5 have invented and produced a new and original Design for a Pattern-Chart, of which the following is a specification, reference being had to the accompanying drawing, forming a part thereof.

o The drawing is a plan view of a pattern-chart, showing my new design.

As shown in the drawing, the leading or material feature of my design consists of a pattern-chart having represented thereon the

5 novel arrangement of patterns for fronts, as now described.

Upon the pattern-chart are shown several

series of heart-shaped fronts A A A, &c., arranged in longitudinal rows upon the pattern-sheet, the alternate rows of fronts being reversed.

Having thus described my invention, what I claim as new therein, and desire to secure by Letters Patent, is—

The design for a pattern-chart substantially as herein shown and described.

In witness whereof I have hereunto signed my name, this 5th day of September, 1898, in the presence of two subscribing witnesses.

JAMES MARSDEN.
